UNITED STATES PATENT OFFICE.

ARTHUR B. McCALL, OF SPRINGFIELD, ILLINOIS.

SERIES PHONE-CONNECTER BLOCK.

Application filed May 4, 1922. Serial No. 558,517.

To all whom it may concern:

Be it known that I, ARTHUR B. McCALL, a citizen of the United States, residing at Springfield, in the county of Sangamon and State of Illinois, have invented a certain new and useful Improvement in Series Phone-Connector Blocks, of which the following is a specification.

My invention relates to phone connector blocks and switches used in connection with radiophone or telephone reception where a plurality of phones are desired to be connected to the same single circuit for "listening in" on concerts, signals and the like.

10 An object of my invention is to provide a simple and economical device that will enable groups of people that are interested in "listening in" particularly on radio concerts and the like, to connect a plurality of "head sets" conveniently onto an apparatus that connects all the sets up in series on the same circuit.

A further object of my invention is to provide an appliance that will effectively accommodate a greater number of "head sets" on a given circuit current than is possible in a multiple or "parallel" connection as for example certain commonly used vacuum tubes in radio service have an internal impedance of 15,000 to 25,000 ohms with a pressure of 40 volts on the "B" batteries at one or one and one half amperes from a 6 volt storage "A" battery which makes it possible to hook on in series one 25 "head set" after another until the external impedance of the phones equals the internal impedance of the vacuum tubes in use; thus making it possible under ordinary operating conditions, to hook on in series connection, seven or more "head sets" when only 40 volts are on the amplifier tube plate circuit.

A further object of my invention is to provide a device for series connection of "head sets," that requires simple processes of manufacture, inexpensive materials and parts and consequently cheap in price as well as affording simple means of detachably securing "head sets" to it.

50 A further object of my invention is to provide an appliance that will afford a detachably rigid connection for either the phone plug or the socalled cord tips, each in common use where "head sets" are used.

55 A comprehensive embodiment of my invention is illustrated in the accompanying

drawings which form a part of this specification in which similar figures of reference indicate corresponding parts in the several illustrations.

60 In the accompanying drawing I have illustrated several of the preferred embodiments of my invention in which it will be observed that the major element of novelty in my invention is adaptable to insulated 65 connector blocks of various shapes and designs for use in various situations.

In the drawings:

Fig. 1 is an enlarged detail of a portion of a connector block illustrating three connecting sections A, B, and C with "head sets" connected thereto.

70 Fig. 2 illustrates a front elevation of one of the connecting sections of connector blocks.

75 Fig. 3 is a vertical half section of the connector taken as passing through opposite connecting sections. This view also illustrates the way a top or cover would rest on the block and be detachably secured 80 thereto.

Fig. 4 illustrates a circular disc shaped connector block having six connecting sections A, B, C, D, E, and F.

85 Fig. 5 is an illustration of a connector block having the general shape of a quarter circular disc and showing also how a connection would be made between the block and receiving cabinet.

90 Fig. 6 is an illustration of a rectangular connector block provided with eight connecting sections and showing a possible means of connecting up the block with the receiving set.

95 Fig. 7 is a perspective showing the relation of bus connector 18 to one of the several inserts 27 which are molded into their respective operating positions. These inserts are swedged to the bus connector 18 and are provided with internal threads to 100 accommodate the several corresponding thumbscrew terminals which are normally vertically disposed, and adapted to make contact with the predetermined corresponding elements of inserted plugs or with cord 105 tips as the case may be.

110 It will be observed that with a connector embodying my invention the "in put" from the receiving set may be made either with cord tips or plug and this "in put" connection can be made at any one of the connecting sections of the block, such as at sec-

tions A, B, C, D, E, F, G or H, Fig. 6 of any one of the six sections on the block in Fig. 4 (section D in this case preferred) or any section in either Fig. 4 or Fig. 1.

It will be observed that my invention involves the combination of elements that make it possible to use on "head sets" either the common cord tips or the commonly used phone plugs as illustrated in Fig. 1, and either may be used also in connecting the connector block with the receiving set.

Such an adaptable convenient combination device as will afford such a choice of connecting means as this is much needed now, especially in the field of radiophone service.

Referring to the details of construction and operation of my invention, the connector block 22 Fig. 1 is made of suitable insulating material.

In the manufacturing processes the block may be moulded into shape and at the same time the bus conductor 18 may be pressed into the surface of the insulating material 25 of the block. If it is desired to make the connector blocks by cutting out the block and drilling the holes for sockets in the sides and the holes for connecting terminals 1, 2, 3, and 4 in the upper surface then such holes 30 should have inserts therein or if the material used is suitable the terminal holes may be threaded in the block material.

It is obvious that each connector block is provided with a series of identical connecting sections such as sections A, B, and C, Fig. 1. Each connecting section is composed of cooperating elements adapted to serve as detachable terminal connection means for phone plugs and cord tips.

For example in Fig. 1 at section A, the illustration shows how the common cord tips 9 and 10 are inserted into sockets 16 and 17 and held into operative position by the thumb screws 3 and 4 and, at the same time thereby making connections with the bus connector 18. When this connection is made the circuit switch 5 is detached from terminal 1 and is left open as long as the connection is desired, thus allowing the circuit 50 to go through the phones.

If in this case it was desired to not use section A for the connection then the circuit switch 5 pivoted at 2 would be hooked again onto terminal post 1 and thus the hook 5 would conduct the circuit on through section A to the adjacent section through bus conductor 18.

In section C of Fig. 1 is shown a phone plug 6 of common design ordinarily used in connection with a phone jack but which is peculiarly well adapted to successfully operate with this connector. It is estimated that a connection block using a common telephone jack as connection means to accommodate as many "head sets" as this block, would cost

several times as much as one of these blocks, because of simplicity of the construction in this block.

When it is desired to use phone plug 6 it is inserted into socket 15, contact is made 70 and the plug held into position by tightening the thumb screw terminals at 1 and 2 so that terminal 1 contacts with the knob 8 of the plug 6 and terminal 2 contacts with trunk 7 of the plug.

Since the trunk 7 and knob 8 of the common phone plug 6 are normally insulated from each other it will be noted that when said plug is inserted into normal operating position terminal 2 contacts with trunk 7 and terminal 1 contacts with knob 8 thus permitting the circuit to pass through the phones at will by merely detaching circuit switch 5 from terminal 1.

In section B Fig. 1 the illustration shows how the cord tips and the plug may be both used in the same section at the same time, thus making it possible to use more phone "head sets" on a small block if desired.

It will be observed that this series connector block may be varied in design and yet stay within the scope of my invention.

For instance Figures 4, 5 and 6 show three designs perhaps more likely to be preferred but a half circle could be used or hexagon or any one of many possible designs of block could be used and yet stay within the scope of my invention.

The design may be varied to suit the situation.

Having thus described the nature of my invention what I claim as new and useful and desire to secure by Letters Patent is:

1. In a series phone connection block of insulating material a plurality of connecting sections adjacently connected in series, each section provided with a horizontally disposed socket for a phone plug, and two smaller sockets spaced on each side thereof adapted to accommodate cord tips of phone "head sets", vertically disposed positive and negative engaging terminals registering respectively with said positive and negative cord tip when in the sockets, two vertically disposed engaging terminals registering in alignment with said plug socket, each spaced to normally contact with the positive and negative poles of said phone plug when in operative position, means connecting said positive and negative terminals with corresponding terminals for the cord tips within the same connecting section, and a circuit switch adapted to open and close the electric circuit passing through said section.

2. In a phone connector block of the class described a connecting section comprising in combination a horizontally disposed phone plug socket and a cord tip socket on each side thereof, vertically disposed positive and negative engaging terminals registering

with the corresponding positive and negative poles of the phone plug when normally in use, means connecting said positive and negative terminals of phone plug posts with 5 corresponding posts of said cord tips, and a circuit switch for optionally opening and closing the electric circuit passing through said connecting section thus providing for the separate or combined use of the phone

plugs or cord tips in common use, as and to for the purpose set forth.

In witness whereof I hereunto set my hand and seal this 15th day of April 1922.

ARTHUR B. McCALL. [L. S.]
